United States Patent Office.

DANIEL G. CHASE, OF BOSTON, MASSACHUSETTS.

Letters Patent No. 75,522, dated March 17, 1868.

IMPROVEMENT IN SHUTTLES FOR LOOMS.

The Schedule referred to in these Letters Patent and making part of the same.

TO ALL TO WHOM THESE PRESENTS SHALL COME:

Be it known that I, DANIEL G. CHASE, of Boston, in the county of Suffolk, and State of Massachusetts, have invented a new and useful Improvement in Shuttles; and do hereby declare the following to be a full, clear, and exact description thereof, due reference being had to the accompanying drawings, making part of this specification, and in which—

Figure 1 is a vertical and longitudinal section of a shuttle containing my invention.

Figure 2, a side elevation; and

Figure 3, a top view of the bobbin-spindle, with the attached springs, as removed from the body of the shuttle.

The object of this invention is to facilitate the insertion or the removal of a shuttle-bobbin, and to adapt a shuttle to the use of bobbins having different-sized heads, as well as to maintain the bobbin and spindle at all times in its proper position; a still further object of the invention, and by no means an unimportant one, being the simplicity and cheapness with which the device may be made.

The invention consists in the peculiar application of a spiral or coiled spring to the heel of the bobbin-spindle, and in combination with an extended or elongated heel of such spindle, to which a flat bobbin-spring is applied, substantially as hereinafter referred to and explained.

In the drawings before mentioned, A denotes the body of a shuttle constructed in the ordinary manner. The bobbin-spindle is shown at a, as supported and turning upon a horizontal pin, b, extending through it and the shuttle, the said spindle having an elongated head, c, extending backward from it, this head c being hollow or made with a longitudinal slot, d, through it, a plate-spring, e, being secured at one end to the extremity of the under side of the head, and extending forward a short distance in advance of the bolster f of such head, the spring, at this point, being given an upward bend, in order to fit into the groove formed in the head of the bobbin, and retain such bobbin in its due relation to the shuttle. A pin or stud, g, is passed transversely through the shuttle and immediately above the spring e, to form a stop or check to the movement of such spring as the spindle is turned upon its fulcrum from a horizontal into an angular position, by this means increasing the distance between the free end of the spring and the bolster of the spindle, and by so doing remove the hold of such spring upon the head of the bobbin, and allow it to be withdrawn from the shuttle or the spindle.

For retracting the bobbin-spindle back into its horizontal position within the shuttle, I make use of a coiled spring, shown at h in the drawings, one end of such spring being attached to the head of the spindle immediately in rear of its bolster, and the opposite end of such spring being secured to a pin, i, extending laterally through the shuttle and over the outer or free end of the extended spindle-head c, the body of the spring h being disposed within the opening or slot of such head, as shown in fig. 1 of the drawings.

It will readily be seen that as the spindle a is moved out of line of axis of the shuttle, in the act of removing the bobbin, upon being left free, the coiled spring will, by its contractile power, return it instantly to place, the extremity of the head c bringing up against a bearing, j, made within the body of the shuttle.

By the arrangement of the plate-spring e with respect to the stationary pin g and the bobbin-spindle, the bend of such spring, as the spindle turns upon its fulcrum, does not bind or catch upon the head of the bobbin, but following the movements of the spindle to such an extent, until it recedes therefrom, as to free the bobbin without friction upon it.

When a cop-shuttle is to be employed, instead of a bobbin-shuttle, the spring e is to be omitted.

I claim the combination of the open slotted spindle-head c, coiled spring h, and plate-spring e, with the shuttle A and stop-pin g, the whole being constructed and arranged for operation, as herein shown and described.

D. G. CHASE.
